HIS ATTORNEY.

UNITED STATES PATENT OFFICE

GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed July 18, 1927, Serial No. 206,848. Renewed April 4, 1929.

This invention relates to rock drills, but more particularly to a distributing valve for fluid actuated rock drills of the hammer type.

The objects of the invention are to obtain a durable valve of light weight, to effect a rapid distribution of pressure fluid to the cylinder and to prevent fluttering of the valve in its limiting positions.

Other objects will be in part obvious and in part pointed out hereinafter.

In the drawings illustrating a practical embodiment of the invention,

Figure 1 is a longitudinal sectional elevation of a portion of a rock drill showing the valve in position to admit pressure fluid to the rearward end of the cylinder, and

Figure 2 is a view similar to Figure 1 showing the valve in its other limiting position.

Referring to the drawings, the invention is shown embodied in a rock drill having a cylinder A closed at its front end by a bushing B and at its rearward end by a back head C. In the cylinder A is disposed a reciprocatory hammer piston D which controls a free exhaust port E in the cylinder and has a forwardly extending reduced shank F slidable in the bushing B.

On the side of the cylinder A is a valve chest G having an annular bore H which extends from the rearward end of the chest to a point near the front end thereof, thus forming an end wall J at the front end of the chest G.

At the open end of the bore H is formed an annular recess K to receive a flange L of a bushing O having in this instance a passage P which communicates with a passage Q in the back head C. Preferably, a throttle valve R of any suitable type is interposed in the passage Q to control communication between the passage P and a source of pressure fluid supply (not shown).

In the front end of the bore H is disposed a bushing S which abuts the wall J and has a threaded extension T projecting through the wall J to receive a nut U whereby the bushing S is secured firmly in position. The bushings O and S are provided with bores V which form the smaller portions of a valve chamber W. In the present instance the bushings O

and S are suitably spaced with respect to each other to form an enlarged portion X of the valve chamber W between the inner ends of the bushings.

Pressure fluid for actuating the piston D is conveyed to the cylinder through inlet passages Y and Z leading from the front and rearward ends respectively of the valve chamber W to the corresponding ends of the cylinder A.

Disposed in the valve chamber W is a distributing valve b having in this instance a bore c therethrough for conveying pressure fluid from the passage P to the inlet passage Y. The rearward and front ends d and e respectively of the valve are preferably so formed as to enable them to lie flush against adjacent ends f and g of the bushings O and S. The ends d and e when out of contact with the respective faces which they are intended to abut serve as holding faces against which pressure fluid may act for holding the valve in its extreme positions. For instance, with the valve in the position illustrated in Figure 1 the end face d is exposed to live pressure fluid flowing into the inlet passage Z and the face e is thus held firmly against the face g of the bushing S.

Intermediate the ends of the valve is formed an enlarged flange h which reciprocates in the enlarged portion X of the valve chamber. The flange h divides the enlarged portion X into forward and rearward pressure chambers j and k into which pressure fluid is intermittently admitted from the interior of the valve by leak ports o and p in the valve registering with passages q and r respectively leading from the bores V to the enlarged portion W. The pressure fluid admitted into the pressure chambers j and k acts against forward and rearward actuating and holding surfaces s and t of the flange h for actuating the valve, as well as to assist in holding the valve after it has been thrown.

In the construction shown, the bushing O is provided with a passage u which leads from the inlet passage Z to the pressure chamber k for exhausting pressure fluid from said pressure chamber into said inlet passage Z upon an occurrence of a drop in pressure in

the rearward end of the cylinder. Similarly, a passage *v* is formed in the bushing *S* to establish communication between the pressure chamber *j* and the inlet passage *Y*. The passages *u* and *v* are preferably of somewhat larger cross sectional area than the ports *o* and *p* so that a greater volume of pressure fluid may be exhausted from the chambers *j* and *k* in a given time than may be admitted thereinto through the ports *o*, *p* and the passages *q*, *r*.

The operation of the device is as follows: With the valve in the position illustrated in Figure 1, pressure fluid will pass over the rearward end *d* of the valve and through the inlet passage *Z* into the rearward end of the cylinder to impel the piston *D* forwardly. During the admission of pressure fluid to the rearward end of the cylinder, the valve *b* is held immovable in the front end of the valve chamber *W* by the pressure fluid acting against the end surface *d* of the valve and against the surface *t* of the flange *h*. During the admission of pressure fluid to the rearward end, however, a portion of the pressure fluid will flow through the port *o* and the passage *q* into the pressure chamber *j* to act against the surface *s* of the flange *h*. Owing to the fact, however, that the front end surface *e* of the valve lies flush against the surface *g* of the bushing *S*, the pressure fluid acting against the rearward end surfaces of the valve will predominate over that acting against the surface *s* and the valve will thus remain in its forward position until the piston *D* opens the exhaust port *E*. Opening of the exhaust port will cause a drop in pressure in the rearward end of the cylinder and consequently on the surfaces *d* and *t* and the pressure fluid in the pressure chamber *j* will immediately cause the valve *b* to start in a rearwardly direction. After the contact between the surface *e* and *g* has been broken, the front end surface *e* will also be exposed to live pressure fluid to assist in throwing the valve rearwardly.

Upon reversal of the valve *b*, pressure fluid will flow over the front end of the valve and through the inlet passage *Y* to the front end of the cylinder and impel the piston *D* rearwardly. At the same time, pressure fluid will flow through the port *p* and the passage *r* into the pressure chamber *k* preparatory to throwing the valve forwardly. During the admission of pressure fluid to the front end of the cylinder, the valve is held in its rearward-most position by pressure fluid acting on the surfaces *s* and *e* and will remain in this position until the piston uncovers the exhaust port during its rearward stroke, thereby causing a sufficient drop in pressure forwardly of the surfaces *s* and *e* to enable the pressure fluid in the chamber *k* to again throw the valve forwardly to its initial position.

As will be observed, the ports *o* and *p* are

of considerably smaller cross sectional area than the passages *u* and *v*, and therefore a slightly greater period of time is required to admit pressure fluid into the pressure chambers *j* and *k* than to exhaust the pressure fluid from these chambers. It is this differential in area between the ports *o* and *p* and the passages *u* and *v* which enables the valve to remain immovable in its extreme positions until the piston *D* has traveled to the ends of the cylinder.

I claim:

1. In a fluid actuated rock drill, the combination of a cylinder and piston, a valve chest having a valve chamber, inlet passages leading from the valve chamber to the cylinder, a distributing valve in the valve chamber having a bore for conveying pressure fluid therethrough, the ends of said valve cooperating with the ends of the valve chamber for controlling the admission of pressure fluid into the cylinder, a flange on the valve intermittently having actuating and holding surfaces, ports in the valve conveying pressure fluid into the valve chamber to act against the said surfaces, and passages in the valve chest for exhausting such pressure fluid into the inlet passage upon an occurrence of a drop in pressure in the ends of the cylinder.

2. In a fluid actuated rock drill, the combination of a cylinder and piston, a valve chest having a valve chamber with an enlarged portion, inlet passages leading from the valve chamber to the ends of the cylinder, a valve in the valve chamber having a bore therethrough constantly exposed to live pressure fluid, the ends of said valve cooperating with the ends of the valve chamber for controlling the admission of pressure fluid into the cylinder, a flange on the valve dividing the enlarged portion into pressure chambers, the ends of said flange constituting actuating and holding surfaces, ports in the valve intermittently admitting pressure fluid into the pressure chambers to act against said surfaces, and passages in the valve chest exhausting pressure fluid from the pressure chambers into the inlet passages upon the occurrence of a drop in pressure in the ends of the cylinder.

3. In a fluid actuated rock drill, the combination of a cylinder and piston, a valve chest having a valve chamber, inlet passages leading from the valve chamber to the cylinder, said valve chamber comprising an enlarged central portion and smaller end portions, a distributing valve in the valve chamber having a bore therethrough constantly communicating with a pressure fluid supply, the ends of said valve cooperating with the ends of the valve chamber for controlling the admission of pressure fluid into the cylinder, a flange on the valve dividing the enlarged portion into a pair of pressure chambers, passages leading from the enlarged portion to the smaller portions of the valve chamber,

ports in the valve intermittently registering with said passages to admit pressure fluid into the pressure chambers for actuating and holding the valve, and passages in the valve chest of larger cross sectional area than the ports for exhausting pressure fluid from the pressure chambers into the inlet passages upon the occurrence of a drop in pressure in the ends of the cylinder.

10 In testimony whereof I have signed this specification.

GEORGE W. HULSHIZER.
